[57] CLAIM

The ornamental design for an express depository, as shown and described.

DESCRIPTION

FIG. 1 is a front elevational view of an express depository showing our new design;

FIG. 2 is a left side elevational view of FIG. 1, the right side being a mirror image thereof;

FIG. 3 is a top plan view of FIG. 1;

FIG. 4 is a left side elevational view of an express depository showing a second embodiment of our new design, the right side being a mirror image thereof; and

FIG. 5 is a top plan view of FIG. 4.

The rear of the express depository shown in FIGS. 1 through 3 is substantially plain and unornamented, while the front and rear of the express depository shown in FIGS. 4 and 5 are the same as the front of the depository shown in FIG. 1.
